METAL FEEDING APPARATUS

Cornelius Jordan and Edward J. Hubelmeyer, Little Ferry, N. J., assignors to United American Metals Corporation, Brooklyn, N. Y., a corporation of New York

Application January 5, 1939, Serial No. 249,486

5 Claims. (Cl. 22—80)

This invention relates to type metal ingot feeding apparatus and more particularly to a hook to be attached to the feeding chain of an automatic type metal feeder.

5 For sometime, metal ingots have been cast in a manner to provide a hole at one end thereof for association with the hooks of automatic type metal feeders whereby the ingots may be readily associated with feeders and suspended therefrom above a melting pot. Such ingots have had the disadvantage of not being completely melted by simply automatic operation of the machine. It was necessary for the operator to manually dislodge the small ear that remained on the 10 feeder hook when the ingot had been lowered to its fullest extent. More recently, slotted eared ingots have been devised to facilitate the automatic slipping off of the ingot ear when the feeder chain has reached its lowest point whereby the 15 operator need not manually dislodge the unmelted ear. Such slip-off ingots are illustrated in the Hostetler Patent No. 2,072,817, granted March 2, 1937.

When this new form of ingot is associated with 20 the conventional feeder hook of an automatic type metal ingot feeder and the feeder chain lowered to its lowermost position, if the ingot is more or less accurately centered on the feeder hook, complete dislodgement takes place automatically. 25 However, many times the ingot is carelessly placed upon the feeder hook in a manner such that the axis of the ingot is out of line with the axis of the hook and complete dislodgement of the ingot does not take place without a manual jiggling 30 of the feeder chain by the feeder operator. This last necessary operation diverts the attention of the operator and accordingly it has been found that prior feeder hooks are unsatisfactory to effect 35 automatic dislodgement of the remaining so-called slip-off ingot ear.

40 It is an object of the instant invention to provide a feeder hook in association with an automatic type metal ingot feeder of such contour as to effect automatic alignment of the slotted eared slip-off ingot with the axis of the hook to insure the correct slip-off action upon the chain reaching its lowermost position.

45 It is a further object of the instant invention to provide a feeder hook having its ingot engaging portion so formed with sloping sides as to effect automatic alignment of slotted eared slip-off type ingots and insure their automatic operation as intended.

50 Other objects and the nature and advantages of the invention will be apparent from the following

description taken in conjunction with the accompanying drawing, wherein:

Fig. 1 is a view in elevation of an automatic type metal ingot feeder having associated with the feeder hook thereof the ear of a slotted eared 5 slip-off type ingot;

Fig. 2 is a view in perspective of a feeder hook in accordance with the invention;

Fig. 3 is a side elevation of the feeder hook; 10 Fig. 4 is a front elevation of the feeder hook;

Fig. 5 is a sectional view taken along lines 5—5 of Fig. 3 and looking in the direction of the arrows;

Fig. 6 is a view similar to Fig. 5 but of a modified form; 15

Fig. 7 is a view similar to Fig. 5 but of a modified form;

Fig. 8 is a view similar to Fig. 5 but of a modified form; 20

Fig. 9 is a schematic illustration of an out of alignment association of a slotted eared ingot and a conventional feeder hook; and,

Fig. 10 is a view similar to Fig. 9 but illustrating a similar slotted eared ingot in association with a feeder hook in accordance with the invention. 25

Referring to the drawing an automatic type metal ingot feeder 20 is arranged above a melting pot 21 to lower an ingot thereinto in accordance with the level of molten metal within the 30 pot as indicated by the float 22. In the position of the feeder illustrated in Fig. 1, the metal ingot has been lowered by the chain 23 and hook 24, with which the ingot was originally in alignment, to a position such that the level of the molten 35 metal within the pot is above the lowermost portion of the hole 25 extending through the ear of the ingot. The respective centers of gravity of the sides 26 and 27 of the ingot ear being relatively remote from the original axis of the ingot, 40 they must part from the hook as illustrated and fall into the melting pot without attention from the operator.

In order to insure automatic alignment of a 45 slotted eared slip-off type ingot, the hook 30 is provided with sloped side portions 31 and 32 and a relatively narrow ridged upper portion 33 adapted to fit between the adjacent hook engaging ends of the ear portions 26 and 27 respectively, whereby the one usually assigned the task of associating metal ingots with the feeder may do so rapidly without very careful attention and yet be certain that the ingot will automatically align 50 itself and stay aligned during the usual course of operation of the machine until the ingot ear 55

reaches a definite place in relation to the molten bath when the time comes for complete automatic separation thereof from the feeder hook. Once the operator has engaged the ear of the slip-off ingot in a manner such that the slot is associated with the ridge of the hook, no further attention need be given to the same by the operator and complete removal of the ear is assured when the hook has reached its lowermost position above the metal bath.

The lowermost portion of the hook is generally U-shaped as illustrated in Fig. 3 and the uppermost portion 34 is provided with a hole 35 whereby it may readily be associated with the feeder chain 23. The ridge 32 extends along the entire length of the lower U-shaped ingot engaging portion of the hook which is of gradual diminishing section from the lowermost portion to the tip 36 thereof. With this configuration the one threading the ingot ear with the hook may align the slot of the ear with the point 36 and slide the same downwardly thereover being guided by the ridge 32.

Not only may the section of the lowermost portion of the hook 24 be generally triangular as illustrated in Fig. 5 but it may take the forms illustrated in Figs. 6, 7 and 8 with the assurance of similar results to those described above, and the improper association of a type metal slotted ear slip-off ingot with a conventional feeder hook in the manner diagrammatically illustrated in Fig. 9 prevented. With this latter arrangement, when the ingot 37 has been lowered to a level within the melting pot above the lowermost portion 38 of the hole 39, the portion 40 of the ear will automatically fall into the melting pot but the portion 41 will hang on to the conventional hook 42 of circular cross section requiring the operator to manually disengage the same.

With the simple threading of the hook in accordance with my invention as illustrated in Fig. 10, automatic separation of the portions 26 and 27 respectively of the ingot ear from the hook 24 is assured and the attention of the operator for this purpose not required.

It will be obvious to those skilled in the art that various changes may be made in this device

without departing from the spirit of the invention and therefore the invention is not limited to what is shown in the drawing and described in the specification but only as indicated in the appended claims.

5

What is claimed is:

1. The combination with an automatic type metal ingot feeder of a hook adapted to lower slotted eared slip-off ingots into a melting pot, said hook comprising a lower ingot ear engaging portion, said hook portion having a section including an upper ridge adapted to extend within the slotted upper end of the ingot, said section having sides adjacent said ridge which are at an angle with the horizontal that is greater than the angle of repose of the combination of the ingot ear on the hook, whereby slipping off of both sides of a slotted eared ingot associated with said hook is assured when said ingot has been lowered within the melting pot to a level above the lowest point of said ear.

2. The combination with an automatic type metal ingot feeder of a hook adapted to lower slotted eared slip-off ingots into a melting pot, said hook comprising a lower ingot ear engaging portion, said hook portion having a section which is substantially triangular including a generally horizontal base, and two sloping sides connecting said base with the upper ridge formed by the meeting of such sides, said sides being at an angle with the horizontal that is greater than the angle of repose of the combination of the ingot ear on the hook, whereby slipping off of both sides of a slotted eared ingot associated with said hook is assured when said ingot has been lowered within the melting pot to a level above the lowest point of said ear.

3. The structure recited in claim 1, the said sides being generally concave in nature.

4. The structure recited in claim 1, the said sides being generally convex in nature.

5. The structure recited in claim 1, said section gradually diminishing to a point at the ingot receiving end of the hook in order to facilitate threading.

CORNELIUS JORDAN.
EDWARD J. HUBELMEYER.
